First Japanese Office Action dated Sep. 27, 2023 for Japanese Design Application No. 2023-007258.

Primary Examiner — Paula Allen Greene

(57) **CLAIM**

The ornamental design for a set of headphones, substantially as shown and described.

DESCRIPTION

FIG. 1 is a perspective view of a set of headphones as seen from the front, top, and right side;

FIG. 2 is a front view thereof;

FIG. 3 is a right side view thereof;

FIG. 4 is a back view thereof;

FIG. 5 is a left side view thereof;

FIG. 6 is a top view thereof; and,

FIG. 7 is a bottom view thereof.

The dotted line portions of the drawings represent portions of the set of headphones that form part of the claimed design.

1 Claim, 6 Drawing Sheets
